10 Claims. (Cl. 183—37)

1

This application is a division of my copending application Serial No. 618,022 filed September 22, 1945, Patent No. 2,564,467, issued August 14, 1951.

My invention relates to vacuum cleaners, and more particularly to improved means for disposing of dirt accumulated in a cleaner.

One of the objects of my invention is to provide a vacuum cleaner having a disposable container for the dirt separated from the air, in combination with means for automatically ejecting this container in sealed condition from the cleaner, whereby disposal of the dirt contained therein may be accomplished, without it ever coming in contact with the hands of the operator, by merely throwing away the container and its contents.

In accordance with one embodiment of my invention the means for separating the dirt from the air and the means for containing the dirt so separated may constitute a bag, preferably made of porous paper, which may be ejected from the cleaner by reversing the flow of air in the neighborhood of the bag so that the latter with the dirt contained therein will be blown out of the cleaner casing. The reversal of air flow may be obtained by either reversing the position of the motor-fan unit within the casing, or by means of properly located valves.

Further objects and features of my invention will be apparent from the following description considered in connection with the accompanying drawings, of which:

Fig. 1 is a cross-sectional view of one embodiment of my invention wherein the dust containing unit is ejected from the casing by means of reversed air flow produced by reversing the position of the motor-fan unit;

Fig. 2 is a top view of a portion of the apparatus shown in Fig. 1; and

Fig. 3 is a cross-sectional view of an embodiment of my invention wherein the reversal of air flow, utilized for ejecting the dirt container, is obtained by valves.

Referring more particularly to Figs. 1 and 2, reference character 10 designates a hollow casing which is movably supported by means of a pair of runners, one of which is shown at 12. The suction end of the casing is provided with a ring 14 which carries a suitable packing ring 16. A cover member 18 is adapted to be removably secured to the casing 10 by any suitable means. Received within this end of the casing is a dust separating and containing member designated generally by reference character 20. This member comprises a bag portion 22, the mouth of which is secured to the periphery of a disc 24.

The bag portion is made of a material which is pervious with respect to air, but which is impervious with respect to dust, while the disc is made of material impervious with respect to both air and dust. Inasmuch as the member 20 is intended to be thrown away each time it is filled with dust, it is desirable to make it of as cheap material as possible, and consequently the bag portion may be made of unglued porous paper while the disc portion may be made of cardboard, although other materials, such as cloth for the bag and metal for the disc clearly fall within the scope of my invention.

The diameter of the disc 24 is such that it will be clamped between the cover 18 and the packing ring 16 when the cover is secured to the casing 10. The cover is formed with an inlet opening 26 which is adapted to receive the end of a hose, to the opposite end of which may be connected any suitable suction nozzle or other cleaning tool. Secured to the inner side of the cover 18 and in alignment with the opening 26 is a tubular member 28 which is adapted to pass through a central opening 30 formed in the disc 24. A flange member 32 is slidably mounted on the exterior of the tubular member 28 and is urged into contact with the disc 24 by means of a coil spring 34. One end of this spring is anchored to tubular member 28, while the opposite end is anchored to the flange member 32 in order to prevent the latter from sliding all the way off the former when the cover 18 is removed.

A flap valve 36 is secured to the inner side of disc 24 and is provided with a spring 38 which tends to pivot the valve to a position closing the opening 30 in the disc, as is shown in Fig. 3. However, when the cover 18 is in place, the tubular member 28 maintains the valve in open position as shown in Fig. 1 and in this position the valve imposes no resistance whatsoever to the flow of air into the bag. The flap valve may be made of cardboard, and the pivoting thereof obtained by flexure of the cardboard itself, inasmuch as normally the valve need be opened and closed only once during the life of the container.

A perforated partition 40 may be provided within the casing 10 between the compartment which receives the container 20 and a motor fan compartment 42. Mounted within the latter compartment is a motor-fan unit comprising an electric motor 44 and a fan 46. This unit is pivotally mounted within the casing by means of a lower pin 48 and an upper pin 50, the overall dimensions of this unit being such with respect to the dimensions of the interior of the casing, that

the unit may be swung through 180° from the position shown, to thereby occupy a reversed position in the casing. A lever 52 is secured to the end of pin 50 which extends through the casing 10 and hence is accessible for manipulation to pivot the motor-fan unit within the casing. A sealing ring 54 is carried by the motor-fan unit and makes sealing contact with the interior of the casing 10 when the unit is in either the position shown in Fig. 1, or when it is rotated 180° from this position.

The fan 46 is provided with an inlet 56, and the air discharged from the fan passes through the housing of motor 44 and out through openings 58 in this housing. This end of the casing 10 is closed by means of a suitable end cap 60 which may be semi-permanently secured in place and is provided with an opening 62.

A rod 64 is slidably mounted in a member 66 and in a projection 68 on the ring 14, which member 66 may also conveniently consist of a carrying handle. A spring 70 is disposed between the member 66 and a collar 72 fixed to the rod, and hence tends to urge the rod to the left as viewed in Fig. 1. The left hand end of the rod is engaged by a projection 74 on the front cover 18 when the latter is in place, thus displacing the rod to the right against the force of the spring 70. With the rod thus displaced, its right end overlaps lever 52, as is more clearly shown in Fig. 2, thus preventing rotation of the lever in a clockwise direction. Rotation in the opposite direction is prevented by means of a stop 76, and an additional stop 78 is provided in order to limit rotation of the lever to 180°. The rod 64 may be provided with a collar 80 which contacts member 68 so as to limit displacement of the rod to the left when the cover is removed.

The above described device operates as follows:

To place the dust separating and containing member 20 within the casing, the cover 18 is removed and the member 20 is inserted until the periphery of the disc 24 seats against the packing ring 16. If desired, the motor-fan unit may be started in order that the flow of air thus produced may be utilized to draw the bag into the casing. Thereafter the cover 18 is secured in place with the tubular member 28 extending through the opening 30 in the disc 24. As above described, this pivots the valve 36 to open position. The spring 34 urges the flanged member 32 tightly against the disc, thus providing a substantial air tight seal between the tubular member 28 and the opening in the disc. If desired, member 32 may be omitted as there is no pronounced tendency for air and dirt to leak between the opening 30 and member 28, but its provision makes it certain that no dust will find its way into the space between the cover 18 and the disc 24.

If a suction nozzle or the like is connected to the opening 26 by means of a suitable flexible hose, air will be caused to flow in through the nozzle and the hose to within the member 20, and if the nozzle is passed over a dusty surface, dust will be entrained with this air. The air is able to pass through the porous material of the bag portion 22, but the dust is filtered from the air and retained in the bag.

When it is desired to dispose of the dust thus collected, the cover 18 is removed. This permits spring 38 to pivot the valve 36 towards closed position, but it will not be entirely closed

due to the fact that the flow of air through the opening 30 will keep the valve partially open.

However, the presence of the tubular member 28 within the bag during the introduction of dust prevents the dust from piling up in the forward end of the bag in a manner which might interfere with the eventual closing of the valve 36. Upon the removal of the cover 18 the spring 10 displaces the rod 64 towards the left a sufficient distance to clear the end of the lever 52. Thereupon, this lever is pivoted by hand through 180° until it strikes the stop 78. This reverses the position of the motor-fan unit within the casing so that the inlet 56 draws air from the atmosphere through the opening 62. This air is expelled under substantial pressure through the openings 58 in the motor housing and passes through the perforated partition 40, thus exerting a pressure on the exterior of the dust container 20, which pressure is ample to eject the container from the open end of the casing 10. As soon as the motor-fan unit is pivoted far enough to break the suction on the dust container, the spring 38 completely closes the valve 36, so that when the container is ejected from the casing it is completely sealed and no dirt is able to escape therefrom.

The sealed bag may be picked up and thrown away without the dirt contained therein ever coming in contact with the operator's hands. Thereafter, the lever 52 is pivoted counter-clockwise, as viewed in Fig. 2, until arrested by the stop 76, whereupon a new dust container may be inserted. The provision of the rod 64 is desirable in order to prevent accidental pivoting of the motor-fan unit while the cover 18 is in place. If this should take place, the reversed flow of air would blow a substantial percentage of the contents of the bag out through the tubular member 28 and the hose, inasmuch as the tubular member 28 prevents the closure of valve 36.

In the embodiment illustrated in Fig. 3 the construction of the dust containing member 20 is the same as that previously described. Also the construction of the front end cover 18 is the same, but this cover is not shown in this figure in order to illustrate the closed position of the valve 36. The dust compartment of casing 10 is separated from the motor-fan compartment 42 by means of a partition 90 which is unperforated, except for a centrally located opening 92 which may be closed by means of a valve plate 94 which is slidably mounted in guides 96. The motor-fan unit 98 is fixed within the casing 10 by means of a suitable support 100 which also provides an air-tight seal between the casing and the unit 98. The right end of the casing is closed by means of a cover plate 102 having a central aperture which communicates with a hollow member 104. A conduit 106 extends from the upper part of the hollow member 104 to within the dust bag compartment. A plate 108 is slidably mounted at the outer end of 104 and is formed with an opening 110 in its lower part and with an upper hook shaped portion 112 which may be engaged by the finger. A hose connection member 114 may be carried by the plate 108 in registry with the opening 110. The plate 108 also carries a sealing member 116 which is adapted to seal the lower end of the conduit 106 when the plate 108 is moved upwardly so as to bring the opening 110 into alignment with the hollow member 104.

Between the partition 90 and the seal formed by support 100, the casing 10 is formed with an

opening 118 which may be closed by means of a pivoted valve member 120. This valve member is connected to the valve member 94 by means of a link 122, the arrangement being such that when the valve 94 closes the opening 92 in the partition 90 the valve 120 uncovers the opening 118 in the casing 10, and vice versa.

During cleaning, a cover, similar to that designated at 18 in Fig. 1, is secured to the left end of the casing 10 and hence the valve 36 is held open. The valve 120 in the casing is closed, thus sliding the valve 94 downwardly so as to uncover the opening 92 in the partition 90. Also, the plate 108 is in its upper position with the sealing member 116 closing the end of the conduit 106 and with the opening 110 in alignment with the hollow member 104. Consequently, operation of the motor-fan unit draws dust laden air into the bag where the dust is separated and retained. The air passes through the porous material of the bag and through the opening 92 to the fan. This air is discharged through the openings 58 in the motor housing and passes through the hollow member 104 and the opening 110 and through the hose connection member 114 to the atmosphere.

When it is desired to eject the bag from the casing, the front end cover is removed, the valves 94 and 120 shifted to the position shown in Fig. 3, and the plate 108 moved to its lower position, as shown in this figure. With the parts in these positions, the fan draws air from the atmosphere through the opening 118, which air is discharged through the openings 58 in the motor housing and enters the hollow member 104. However, due to the fact that the outer end of this member is closed by the plate 108, the air passes through conduit 106 to within the dust bag compartment, and the pressure thus created in this compartment ejects the bag from the open end of the casing.

While I have shown and described two more or less specific embodiments of my invention it is to be understood that this has been done for purposes of illustration only, and that the spirit or scope of my invention is not to be limited thereby but is to be determined from the appended claims.

What I claim is:

1. In a vacuum cleaner, a casing, means for producing flow of air through said casing, means for separating dust from the air and for containing the dust so separated, and means for utilizing energy obtained from the air flow producing means to eject the containing means from said casing.

2. In a vacuum cleaner, a casing, means for producing flow of air through said casing, means for separating dust from the air and for containing the dust so separated, and means for supplying air from the air flow producing means to eject the containing means from said casing.

3. In a vacuum cleaner, a casing, means for producing flow of air through said casing, a dust bag removably secured in said casing in the path of the air for separating dirt therefrom and for containing the separated dirt, and means for utilizing energy obtained from the air flow producing means to eject said bag from said casing.

4. In a vacuum cleaner, a casing, means for producing flow of air through said casing, a dust bag removably secured in said casing in the path of the air for separating dirt therefrom and for containing the separated dirt, said bag having an opening through which the dirt laden air

enters the bag, means for closing said opening, and means for utilizing energy obtained from the air flow producing means to eject said bag in closed condition from the casing.

5. In a vacuum cleaner, a casing, means for producing flow of air through said casing, a dust bag removably secured in said casing in the path of the air for separating dirt therefrom and for containing the separated dirt, and means for reversing the flow of air produced by the first-mentioned means in the neighborhood of said bag to eject the bag from said casing.

6. In a vacuum cleaner, a casing, means for producing flow of air through said casing, a dust bag removably secured in said casing in the path of the air for separating dirt therefrom and for containing the separated dirt, said bag having an opening through which the dirt laden air enters the bag, means for closing said opening, and means for reversing the flow of air produced by the first-mentioned means in the neighborhood of said bag to eject said bag in closed condition from said casing.

7. In a vacuum cleaner, a casing, a motor-fan unit having an inlet at one end and an outlet at the other for producing flow of air through said casing, means for pivotally mounting said unit in said casing, means for separating dust from the air and for containing the dust so separated, and means for pivoting said unit in said casing to reverse the positions of said inlet and outlet to thereby provide flow of air in reversed direction for ejecting the containing means from said casing.

8. In a vacuum cleaner, a casing, a motor-fan unit having an inlet at one end and an outlet at the other end for producing flow of air through said casing, means for pivotally mounting said unit in said casing, a dust bag removably supported in said casing in the path of air drawn into the casing when the unit is in one position, and means for pivoting said unit to another position in said casing to thereby provide flow of air in reversed direction for ejecting said dust bag from the casing.

9. In a vacuum cleaner, a casing, a motor-fan unit having an inlet at one end and an outlet at the other end for producing flow of air through said casing, means for pivotally mounting said unit in said casing, a dust bag removably supported in said casing in the path of the air drawn into the casing when the unit is in one position, said bag having an opening through which the air enters the bag, means for sealing said opening, and means for pivoting said unit to another position in said casing to thereby provide flow of air in reversed direction for ejecting said dust bag in sealed condition from the casing.

10. In a vacuum cleaner, a casing, means dividing said casing into a first compartment and a second compartment, a dust bag removably supported in said first compartment, said first compartment having an inlet opening communicating with the interior of said bag, a motor-fan unit having a discharge opening communicating with said second compartment and having a suction opening, and valve means shiftable to one position for connecting said first compartment with said suction opening and for connecting said second compartment with the atmosphere to draw air into and through said dust bag and shiftable to another position for connecting said suction opening directly to atmosphere and for connecting said second compartment to said first compartment to produce air flow in said first

compartment for ejecting said dust bag therefrom.
